CLAIM

The ornamental design for a dispensing box, as shown and described.

DESCRIPTION

FIG. 1 is a perspective view of a dispensing box of my new design.

FIG. 2 is a frontal view thereof.

FIG. 3 is a rear view thereof.

FIG. 4 is a right-side view thereof.

FIG. 5 is a left-side view thereof.

FIG. 6 is a top view thereof; and,

FIG. 7 is a bottom view thereof.

The dashed lines in the drawings depict claimed perforations that define a removable portion of the dispensing box.
